Charles Dilling & George Stollers of Philadelphia
Letters Patent

The Plaintiff referred to in these Letters Patent and making part of the same containing a description in the words of the late Charles Dilling and George Eastot Dilling, the substance of their improvement in the construction of Locomotive Engines.

To all whom it may concern. Be it known that the Charles Dilling and George Eastot Dilling of the City of Philadelphia and State of Penna. aforesaid, have invented a mode of increasing the adhesion of the hind or working wheel in Locomotive Engines to the rail, whereby they are enabled to draw trains of cars upon a winding track in situations where, without this improvement they would roll on the rail without adhesion, and we do hereby declare that the following is a full and true description thereof. The principle upon which we proceed in increasing the adhesion to the rail of a Rail Road, of the hind or working wheel of a Locomotive Engine, is the so coupling the cars, containing the load to be drawn, to the body of the Locomotive Engine, as that the load by its action upon a lever or standard shall tend to raise the fore end of the Locomotive in any desired degree, and thus to lessen the pressure upon the fore end, and transfer the same to the hind wheel. The arrangement of the parts, by which this end may be attained, is capable of much variation, but the principle will be rendered evident by reference to the accompanying drawings, in which fig 1. represents a side view, and fig 2. a plan of a part of the Locomotive and frame work as is necessary for the present description. The wheels of the Locomotive are not shown as they would obstruct the view of the parts, particularly to be spoken of. A is the furnace part of the body of the Locomotive. B is a lever or standard attached or not at the lower end C to the body of the furnace and strengthened and sustained by the branch D, from the upper end C of the lever a strake iron or other continuation is to extend to the end of the lower part. Instead of attaching the lever or standard to the body of the furnace, it may be attached to frame by which

it is submitted and claimed at all events which are found and C to become
part of the case may be made to stand up or down so as to increase
or decrease the leverage. This is a brace to it having thus fully ac-
complished the principle of our said Invention, we wish it to be dis-
tinctly understood that we do not intend to limit ourselves to any
particular form or manner of constructing the parts concerned in
producing the intended effect, but that we claim as our invention
and wish to secure by Letters Patent, as the connecting to a Locomotive
Engine the load to be drawn by it in such a manner as to throw
a larger portion of the weight of the Locomotive upon its hind wheels
than they are ordinarily intended to sustain, in the manner or upon
the principle herein before set forth.
